DISINFECTING APPARATUS

Filed Nov. 8, 1927

Inventor

U. J. Smith

By *Watson E. Coleman*
Attorney

UNITED STATES PATENT OFFICE

ULYSSES JOSEPH SMITH, OF CLEVELAND, OHIO

DISINFECTING APPARATUS

Application filed November 8, 1927. Serial No. 231,947.

This invention relates to certain improvements in disinfecting apparatus and it is an object of the invention to provide a device of this kind adapted to be placed in a pocket or recess within a wall and wherein the apparatus is provided with a carry-off vent into which the apparatus discharges, said vent providing means to prevent clogging of the discharge from the apparatus after the same has been sealed or mounted in applied or working position.

5 or recess within a wall and wherein the apparatus is provided with a carry-off vent into which the apparatus discharges, said vent providing means to prevent clogging of the discharge from the apparatus after the same has been sealed or mounted in applied or working position.

10 This invention consists in the details of construction and in the combination and arrangement of the several parts of my improved disinfecting apparatus whereby certain important advantages are attained and the device rendered simpler, less expensive and otherwise more convenient and advantageous for use, as will be hereinafter more

15 fully set forth.

The novel features of my invention will hereinafter be definitely claimed.

In order that my invention may be the better understood, I will now proceed to describe the same with reference to the accompanying drawings, wherein:—

Figure 1 is a vertical sectional view taken through a mausoleum illustrating an apparatus constructed in accordance with an embodiment of my invention in applied position with respect to each of the crypts;

Figure 2 is a view in perspective of an apparatus unapplied;

Figure 3 is a vertical sectional view through the apparatus as herein disclosed and in applied position, the coacting wall portion being shown in fragment;

Figure 4 is a sectional view taken substantially on the line 4—4 of Figure 3.

40 As disclosed in the accompanying drawings, M denotes a mausoleum in which is provided a vertical series of crypts C.

The side wall 1 of each of the crypts is provided in its inner face with a recess or pocket 2 in which is adapted to be applied a disinfecting apparatus A constructed in accordance with an embodiment of my invention. This apparatus A, as herein disclosed, comprises a container of requisite dimensions

45 and which is divided by a vertical partition

3 into two compartments 4 and 5, the compartment 4 being adapted to contain disinfecting crystals while the compartment 5 is adapted to contain granular material, such as sand, sand and plaster Paris and the like. 55 The lower portion of each of these compartments 4 and 5 communicates with the passageway 6, one end portion of said passageway opening, as at 7, to the front wall thereof while the opposite end of the passageway 60 opening through the side wall 8 remote from the opening 7.

Suitably secured to the front and rear walls 9 of the container and extending along the side wall 8 is an additional compartment 10 65 forming a flue into which the passageway 6 discharges through the opening 11 in the side wall 8 of the container.

The apparatus A when in applied position substantially snugly engages within 70 a recess or pocket 2 and after being so applied, a layer 12 of cementitious material or the like is applied over such apparatus within the pocket or recess 2 as is particularly illustrated in Figure 4 whereby the apparatus A is effectively maintained in applied position. In applying this layer 12 care is

exercised not to close or obstruct the opening 7. By providing the additional compartment or flue member 10, positive means 75 are afforded to prevent clogging or obstructing of the passage from the passageway 6 due to the fact that said compartment or flue member 10 extends from the passageway 6 to the upper part of the container. When

80 the apparatus A is applied in working position, the compartment or flue member 10 is in communication with an upwardly disposed vent or duct 14 extending upwardly through the side wall of the crypt and the side walls of such crypts as may be superimposed thereon whereby each of the crypts

85 has communication through an applied apparatus A with the upper carry-off air chamber D.

90 As is particularly illustrated in Figure 1, it is to be noted that each of the crypts has a separate vent or duct 14 in communication therewith so that the circulation through

95 100

each of the crypts is no way affected by the circulation through the others.

The rear wall of each of the crypts C has associated therewith a disinfecting apparatus A' of a type particularly described and claimed in my application for patent executed on even date herewith.

My improved apparatus, as herein disclosed, is of a type wherein, after the dis-
10 infecting crystals have been consumed, the granular material in the compartment 5 will flow into the passageway 6 to seal the same.

From the foregoing description it is thought to be obvious that a disinfecting ap-
15 paratus constructed in accordance with my invention is particularly well adapted for use by reason of the convenience and facility with which it may be assembled and operated, and it will also be obvious that my inven-
20 tion is susceptible of some change and modification without departing from the prin-
ciples and spirit thereof and for this reason I do not wish to be understood as limiting myself to the precise arrangement and forma-
25 tion of the several parts herein shown in carrying out my invention in practice ex-
cept as hereinafter claimed.

I claim:

1. A disinfecting apparatus of the class described comprising a container provided therethrough with an air passageway and with compartments in communication with the passageway, one of said compartments being adapted to contain a disinfecting ma-
35 terial and the other a granular material, and an additional compartment extending along the container, said compartment forming a flue into which the air passageway dis-
charges, said compartment or flue extend-
40 ing to the upper part of the container.

2. A disinfecting apparatus of the class described comprising a container provided therethrough with an air passageway and with compartments in communication with the passageway, one of said compartments being adapted to contain a disinfectant ma-
45 terial and the other a granular material, and an additional compartment extending along the container, said compartment forming a flue into which the air passageway dis-
charges, said compartment or flue being comprised in the structure of the container, said compartment or flue extending to the upper part of the container.

55 In testimony whereof I hereunto affix my signature.

U. J. SMITH.
